ATTORNEY

UNITED STATES PATENT OFFICE

WILLIAM HENRY HOLMES, OF MOUNT VERNON, NEW YORK

EDUCATIONAL STRIP-HOLDER

Application filed May 15, 1928. Serial No. 277,983.

The present invention is concerned with the provision of a holder which may have a wide range of usefulness, but which is primarily intended and peculiarly adapted for holding strips or sheets of printed matter. It is especially suitable for temporarily supporting in various positions of adjustment the endless educational strips disclosed in my prior United States Letters Patent No. 1,678,621, issued July 24, 1928, which strips are reversible and bear printed data on one face and corresponding graphic indicia on the other face.

10

In my prior patent above referred to various types of holders are disclosed for mounting the strips, the present invention representing an improvement over such holders and being characterized by the following advantages.

15

20 It may be conveniently handled by a child even of the kindergarten age, the insertion, removal, replacement, and adjustment of strips or other indicia bearing members being a very simple operation.

25 It is light in weight and made of some such material as heavy cardboard or the like, so that a class of children may manipulate the holder on wooden desks without undue noise and distraction.

30 It serves as a convenient permanent holder to prevent loss of the strips and sheets when the latter are not being used.

It is of simple, practical construction, rugged and durable in use, and well suited to 35 the requirements of economical manufacture.

With the above noted and other objects in view, the invention consists in certain novel features of construction and combinations and arrangements of parts as will be more 40 fully hereinafter set forth and pointed out in the claim. The invention may be more fully understood from the following description in connection with the accompanying drawings, wherein—

45 Fig. 1 is a plan view of the holder.

Fig. 2 is a fragmentary view similar to Fig. 1, but showing the manner of use of the holder.

The holder includes a fairly stiff sheet 50 or plate 10 of cardboard, fibre-board, or other

suitable material. The plate may be of any desired proportions, and is preferably slotted and punched to provide a plurality of longitudinally extending series of upwardly projecting tongues 11 which tongues are slightly 55 forwardly offset from the plane of the plate and may be of the generally semi-circular shape illustrated. The corresponding tongues of adjacent series are preferably spaced equal distances from the top and bottom of the plate and from each other.

The transverse rows of tongues formed by the corresponding tongues of each longitudinal series may conveniently support educational strips such as the strips 12. The strips forming part of the present invention were described in my prior patent and comprise endless accordion folded strips, the fold defined spaces of which bear corresponding graphic and written indicia on opposite sides. 70

With the form of the invention shown, three series of tongues are used and the plate 10 is of a width equal to slightly less than half the length of strips 12, so that these strips may be unfolded as far as possible 75 and displayed on the plate. To effect such display, the strips may be slipped over the tongues 11 as illustrated, slipped behind the tongues or looped over the plate completely 80 embracing the plate and having the lower edges of their forward rims confined behind a transverse row of tongues.

With two or more strips disposed as in Fig. 2, that is to say, slipped over two adjacent transverse rows of tongues, the full half of 85 each strip is exposed. By arranging the tongues of each longitudinal series at a distance apart equal approximately to the width of a single strip 12, two adjacent strips are quite close together and ready comparison of 90 the two strips may be had. The manner in which these strips are used to teach spelling, reading, etc., by comparison of graphic and written indicia, will be self-evident.

If desired, a pair of downwardly facing tongues 13 may be provided above the tongues 12 between the center series of tongues and the outer series, tongues 13 cooperating with 95 correspondingly situated upwardly facing 100

tongues 14 adjacent the bottom edge of the plate.

5 Preferably, a pair of longitudinally extending slots 16 are formed in the plate, these slots defining a resilient central strap portion 17 under which the folded strips 12, etc., may be held while not in use to prevent such slips from becoming lost or misplaced, and to permit a series of holders to be stacked or handled with the strips firmly secured within them.

10 It is to be understood that the holder may be made of transparent material, such as celluloid, so that the intelligence matter appearing on the opposite sides of each strip 12 may be viewed, while positioned as shown in Figure 2, by merely turning the holder around to present the obverse and reverse sides of the holder, and therefore, the strip.

15 20 Various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claim.

25 I claim:

30 A holder of the class described comprising a plate, a plurality of spaced longitudinal series of tongues struck from the plate and lying in substantially parallel relation with and forwardly offset from the plate, said plate having a pair of longitudinal parallel slots therein between the series defining a flexible strap between them.

35 Signed at New York, in the county of New York and State of New York this 14th day of May, 1928.

40 WILLIAM HENRY HOLMES.
